(57) **CLAIM**

The ornamental design for a surface cleaning device, as shown and described.

DESCRIPTION

FIG. 1 is a front perspective view of a surface cleaning device; FIG. 2 is a front view of the surface cleaning device, the back being a mirror image;

FIG. 3 is a top view of the surface cleaning device; FIG. 4 is a bottom view of the surface cleaning device; and, FIG. 5 is a side view of the surface cleaning device, the opposite side being a mirror image.

Broken lines are used to illustrate features of the surface cleaning device which form no part of the claimed design. The break lines indicate that the appearance of any portion of the surface cleaning device between the break lines forms no part of the claimed design.
